CORNHUSKING MECHANISM

Dugald Currie, Des Moines, Iowa

Application June 12, 1947, Serial No. 754,188

2 Claims. (Cl. 130—5)

1

This invention relates generally to corn picking machines and in particular to a corn husking mechanism for such machines.

Many of the corn husking mechanisms now in general use usually include a plurality of husking rolls arranged in a substantially horizontal parallel relation and having their peripheries variously formed to provide a husk removing or gripping action therebetween. The rolls are connected together at one of their ends by a train of gears to provide for their being driven from a common drive, with adjacent rolls rotated in opposite directions. Husking mechanisms of this type are generally satisfactory in operation but difficulties are encountered in obtaining a desired gripping action between the rolls over any sustained period of use because of the husks becoming wrapped about the rolls. A further objection is found in the fact that the wrapped husks tend to travel toward one end of the rolls and collect at such end. As a result excessive wear takes place both on the rolls and the bearings for the rolls.

It is an object of this invention, therefore, to provide an improved corn husking mechanism.

A further object of this invention is to provide a corn husking mechanism in which wrapping of removed husks about the rolls is substantially eliminated.

Another object of this invention is to provide a husking mechanism in which the rolls are of a substantially smooth contour over their full lengths and concurrently operable without the need for the usual series of gears at one of their ends.

A further object of this invention is to provide a husking mechanism which is of a compact and rugged construction, economical to manufacture, and efficient in operation over prolonged periods of use with a minimum of servicing and maintenance attention.

A feature of this invention is found in the provision of a husking mechanism in which a pair of rolls are arranged in a parallel spaced relation and an intermediate roll is extended axially between and above the plane of such pair of rolls. A flat continuous combination husking and drive belt, which travels about the pair of rolls and against the underside of the intermediate roll, is of a width substantially coextensive with the length of the rolls. On rotation of the rolls a husking action takes place between the belt and one of the sides of the intermediate roll, with the removed husks being carried on the belt for discharge from the mechanism.

2

Further objects, features and advantages of this invention will become apparent from the following description when taken in connection with the accompanying drawings, in which:

Fig. 1 is a perspective view of the husking mechanism of this invention with certain parts broken away for the purpose of clarity;

Fig. 2 is a transverse sectional view as seen along the line 2—2 in Fig. 1;

Fig. 3 is a foreshortened longitudinal sectional view taken on the line 3—3 in Fig. 2; and

Fig. 4 is an enlarged sectional detail view as seen on the line 4—4 in Fig. 1.

With reference to the drawings, the husking mechanism of this invention is illustrated in Fig. 1 as including a substantially rectangular frame structure 10, having end angle members 11 and 11a connected between opposite ends of side angle members 12. Arranged on each of the end members 11 and 11a, in a spaced relation transversely of the frame structure 10, are a plurality of bearing members 13 and 14, with the bearings 14 being positioned between adjacent bearings 13, and of a greater height than the bearings 13 for a purpose which will appear later. Three pairs of bearings 13 and two pairs of the bearings 14 are illustrated in the drawings.

Rollers 16, 17 and 18, all of a like construction, are rotatably supported in the bearings 13. For the purpose of convenience the rollers 16 and 18 will hereinafter be referred to as end rollers, and the roller 17 as a center or intermediate roller. Rotatably supported in the bearings 14 are a pair of like rollers 19 and 20, of a diameter somewhat smaller than the diameter of the rolls 16, 17 and 18, and arranged between the intermediate roll 17 and an end roll 16 and 18.

All of the rolls 16—20, inclusive, (Figs. 1 and 2) are in a spaced parallel relation extended longitudinally of the frame structure 10, with the rolls 16, 17 and 18 being arranged in one common plane, indicated at A, and the rolls 19 and 20 in a second common plane, indicated at B, which is above and parallel to the plane A. In the following description, therefore, the rolls 19 and 20 will be referred to as the upper rolls.

The rolls 16, 17 and 18, and the upper rolls 19 and 20, are concurrently operated by a common continuous belt 21 (Figs. 1 and 2) of a width substantially equal to the length of the rolls. The lower length of the belt 21, as viewed in Figs. 1 and 3, travels across the undersides of the rolls 16, 17 and 18, while its upper length travels across the top sides of the rolls 16, 17 and 18, and in

frictional engagement with the undersides of the upper rolls 19 and 20.

Rotation of the rolls is accomplished by a drive gear 22 mounted on a rearward extension 23 of the shaft 24 for the end roll 18. The gear 22, or a like member, is suitably connected with a source of power supply. On rotation of the roll 18, therefore, all of the rolls 16, 17 and 18 are rotated in a like direction, and the upper rolls 19 and 20 are rotated in a reverse direction. Thus, as illustrated by the arrows in Fig. 3, the rolls 16, 17 and 18 are rotated in a counter-clockwise direction, and the upper rolls 19 and 20 are rotated in a clockwise direction. It is seen, therefore, that the belt 21 constitutes a common drive for the rolls 16, 17, 19 and 20, with only the roll 18 being directly connected with a source of power supply.

The tension of the belt 21 is adjusted by having the bearings for the end roll 16, indicated at 13a, adjustably supported for movement longitudinally of the end members 11 and 11a. This is accomplished by the provision of bolts 26 (Fig. 4) threadable in the bottom side of the bearings 13a and extended through slots 27 formed in the angle end members 11 and 11a. Adjustment bolts 28 have one end secured in the bearings 13a and their opposite ends slidably extended through upright supports 29 carried on the end members 11 and 11a. Nuts 31 for the adjustment bolts 28 are engageable with the upright supports 29. On adjustment of the nuts 31 to a desired tension for the belt 21, the bolts 26 are tightened to hold the bearings 13a in their adjusted positions.

The belt 21 is maintained against movement axially of the rolls by V-shaped flexible guides 32 (Figures 2 and 3) provided at its opposite sides. The guides 32 are received in corresponding annular grooves 33 formed in the opposite ends of the rolls 16, 17 and 18.

A corn hopper 34, of an open frame structure, is supported on the frame structure 10 at a position above the rolls by the provision of supports 36 which are carried on the side frame members 12. The side walls 37 and 38 of the hopper 34 are extended longitudinally above the upper roll 19 and the end roll 18, respectively. The forward end of the hopper 34 is open and its rear end wall 40 is positioned forwardly of the end frame member 11a.

In the operation of the husking mechanism of this invention the frame structure 10 is inclined downwardly and forwardly. With the rolls and the belt 21 in operation, ears of corn are supplied to the hopper 34 at its upper or rear end, and moved to its open or forward end by the action of gravity. The rotation of the upper rolls 19 and 20 and the movement of the upper length of the belt 21 provides for the positioning of the ears longitudinally of the upper rolls 19 and 20, so that the ears in lengthwise positions are moved along the downwardly moving sides 19a and 20a of the upper rolls.

Stated otherwise, the substantially V-shape spaces 39, formed between the adjacent sides of the rolls 19 and 17, and 20 and 18, constitute corn troughs. The positioning of the ears to travel lengthwise in the troughs 39 is facilitated by the provision of weighted arms 41 which are pivotally carried between a pair of the supports 36 for up and down pivotal movement, and arranged so that their lower ends 42 extend across the troughs 39 in supported positions on the upper rolls 19 and 20.

During the downward movement of the corn ears the husks are removed by the gripping action which occurs between the belt 21 and the sides 19a and 20a of the upper rolls. This gripping action is supplemented by the provision of oppositely arranged longitudinally extended grooves 43 (Figs. 1 and 2) formed in the upper rolls 19 and 20.

The removed husks are carried on the top length of the belt 21 and discharged over the end roll 16 to one side of the husking mechanism. It is seen, therefore, that the belt 21 functions to both drive the rolls 16, 17, 19 and 20, from the end roll 18, and in combination with the upper rolls to remove husks from the ears of corn supplied to the hopper 34.

To assure a travel of the husks, removed by the action of the roll 20, over the intermediate roll 17 and under the upper roll 19, there is provided a deflector member 44 (Figs. 1, 2 and 3) of a generally square shape in transverse cross section, which is carried between a pair of upright supports 46 on the frame end members 11 and 11a. The deflector 44 extends longitudinally of the frame structure 10 in an upwardly spaced relation between the center roll 17 and the upper roll 20, with a pair of opposite corners thereon arranged in a substantially common vertical plane.

As the husks pass outwardly from between the roll 20 and the upper length of the belt 21, they are engaged and directed by the inclined side 48 of the deflector member 44 for travel over the center roll 17 and underneath the upper roll 19. In other words, the deflector 44 acts to bend the leading ends of the husks, as the husks emerge from underneath the roll 20, in a direction over the center roll 17 and toward the underside of the upper roll 19.

In one embodiment of the invention the rolls 16 to 20, inclusive, are about three feet in length, with the rolls 16, 17 and 18 being about three inches in diameter, and the upper rolls 19 and 20 about two and three-eighths inches in diameter. The annular grooves 33 in the rolls are about three-eighths inches deep and the belt 21 is about one-eighth of an inch thick. In this embodiment the planes A and B for the rolls 16, 17 and 18, and the upper rolls 19 and 20, respectively, are spaced about three-quarters of an inch apart.

From the above description it is seen that the invention provides a husking mechanism which is of a simple and compact construction, and in which all of the rolls are of a substantially smooth peripheral contour. Further, only the end roll 18 is provided with a gear for connection with a source of power supply, and all of the remaining rolls are driven from the end roll 18 by the common continuous belt 21. Further, the belt 21 acts in combination with the upper rolls 19 and 20 to remove the husks from the ears of corn as they move lengthwise in the corn troughs 39. As the husks are removed they are carried by the top side of the belt 21 for discharge from the husking mechanism at varying positions over the length of the end roll 16.

Although the invention has been described and illustrated with three rolls, 16, 17 and 18, and a pair of upper rolls 19 and 20, it is apparent that any desired number of rolls may be used depending upon the size of the husking mechanism desired.

It is to be understood also that although the invention has been described with respect to a

preferred embodiment thereof, that it is not to be so limited since changes and modifications can be made therein which are within the full intended scope of this invention, as defined by the appended claims.

I claim:

1. A corn husking mechanism including a frame structure, a plurality of rolls, means rotatably supporting said rolls in a parallel relation spaced transversely of said frame structure, with the end rolls and an intermediate roll having their axes in a common plane, and certain of the remaining rolls having their axes in a second common plane spaced upwardly from said first mentioned common plane and between adjacent rolls in said first common plane, with said rolls being relatively constructed such that the rolls in said second common plane have their lower sides substantially at the level of said first common plane, and their upper sides above the level of the upper sides of the rolls in said first common plane, a continuous combination drive and husking belt of a width substantially coextensive with the length of said rolls arranged to travel below said end rolls and between the rolls in said two planes, whereby to be in contact engagement with all of said rolls, and means for driving one of said rolls.

2. In a corn husking mechanism including a frame structure, a pair of rolls having their axes in a common plane and rotatably supported in a parallel relation spaced transversely of said frame structure, a third roll positioned in a parallel rela-

tion with and between said pair of rolls with its axis spaced upwardly from said common plane, a continuous combination husking and drive belt of a width substantially coextensive with the length of said rolls having its lower length extended along the undersides of said pair of rolls and its top length in contact with the underside of said third roll and the upper sides of said pair of rolls, with the third roll having a diameter relative to the diameters of said pair of rolls such that the upper side thereof is above the upper sides of said pair of rolls and the opposite lateral side portions of said third roll form with the belt portions adjacent thereto substantially V-shape troughs having their apex ends terminating substantially in said common plane, and means for driving one of said rolls.

DUGALD CURRIE.
